UNITED STATES PATENT OFFICE

MICHEL DASSONVILLE, OF PARIS, FRANCE, ASSIGNOR TO SOCIETE D'EXPLOITATIONS DES TEXTILES NOUVEAUX, OF GENEVA, SWITZERLAND, A CORPORATION OF SWITZERLAND

APPARATUS FOR THE PREPARATION OF CELLULOSE XANTHATE

Application filed September 28, 1929, Serial No. 395,982, and in France July 1, 1929.

This invention relates to apparatus for the production of cellulose xanthate, comprising a double jacketed churn which is slowly rotated round an axis during the reaction of the carbon disulphide on the alkali cellulose, and the object of the invention is a construction which enables a final product to be obtained which is absolutely homogeneous, free from particles of alkali cellulose unattached by 5 carbon bisulphide and also free from any excess of bisulphide.

In its preferred form the said apparatus consists of a metallic container or churn, formed by two spherical caps, capable of 15 withstanding pressure and vacuum, which slowly revolves around an axis during the whole preparation of the xanthate. The construction of the said apparatus enables the temperature of the re-acting mass to be continuously controlled, in order to regulate the 20 action of the carbon bisulphide and to bring the xanthate by the end of the preparation to the temperature most convenient for mixing i. e. for the solution of the xanthate in alkali 25 lye.

The invention is illustrated by way of example in the accompanying drawings, which are intended to make clear the application and operation of the invention.

Figure 1 is a longitudinal section of the apparatus.

Figure 2 is an end view, and

Figure 3 is a plan view of the apparatus.

Referring to the drawings it will be seen 35 that both spherical caps 1 and 1b, of same radius with perfectly smooth internal walls, so that no alkali cellulose particles will be retained, are assembled on small circles of the same diameter. The connecting joint 2, 40 made between male and female conical members, held together by means of nuts and bolts 17a, renders the apparatus fluid tight during the whole preparation of the cellulose xanthate.

Both spherical cap members constituting 45 the container or churn are provided with a double jacket 3, between which continuity is ensured, even during the opening of the apparatus, by means of two flexible tubes 4, enabling a heating or cooling fluid to be circu-

lated during the action of the alkali cellulose by the carbon bisulphide.

The poles of the caps are respectively provided with flanges 5 and 6 to which are secured the journals 7 and 8, each journal being 55 supported by a bearing 9 in which the said journal may revolve, each bearing being carried by a support 10.

The apparatus can be given two different motions. (1) A revolving motion of both 60 caps around the principal axis and (2) a linear motion of one of the caps in respect to the other, along the axis.

The slow revolving motion is transmitted to the churn by means of a worm wheel 11 fast on journal 7 and a worm 12 on the shaft 13 of a pair of fast and loose pulleys 14 and 15 respectively. A striking gear 16 enables the apparatus to be started and stopped according to the needs of the operator.

The linear motion of one of the spherical caps in respect to the other in the axial direction enables xanthate to be discharged and the apparatus to be cleaned. A thorough 70 cleaning is easy to accomplish and the worker operates in open air thus avoiding dangers 75 of poisoning.

The linear motion is defined and limited by the length of the removable distance pieces 17 which normally engage beneath the heads of 80 the bolts 17a.

The axial movement of one of the caps is provided for by the end of the journal 8 being furnished with a square threaded screw 18 meshing in a nut 19 fixed axially but which 85 can be rotated from a hand wheel 22 through gears 20 and 21. A locking device 23 enables the square threaded screw and its nut to rotate as a whole during the rotation of the churn, care being previously taken to disconnect the hand wheel and the pinion 21 by means of a lever disengaging device 24.

The apparatus is further provided with a 90 conducting pipe for the carbon bisulphide, constituted by a cylindrical conduit located in the axis of the apparatus and fed by a 95 gauging device 26 placed under pressure. The carbon bisulphide is volatilized and the alkali cellulose particles driven by the revolving motion, roll upon the smooth walls 100

of the apparatus, successively offering all their surfaces to the action of the atmosphere saturated with carbon bisulphide. An advantageous arrangement for the introduction of carbon bisulphide is that shown in the drawings, wherein the journal 7 is provided with a central admission conduit.

The apparatus also comprises means for the removal by suction and the recovery of carbon bisulphide vapours.

To this end, the churn is internally provided with a funnel 27 connected to the recovering apparatus by means of a conduit 25 and a vacuum pump. At the end of the action the carbon bisulphide vapours saturating the atmosphere of the churn are sucked out and the excess liquid sulphide impregnating the particles of xanthate is volatilized.

In order to avoid cellulose xanthate flakes from being carried off under the action of the vacuum the funnel 27 is provided with a screen 28 perforated with holes of small diameter constituting a sieve. In this way losses of the manufactured product, obstruction of the pipes and coating of the vacuum pump are avoided.

An important factor enabling the cellulose xanthate to be obtained in the best conditions is that it is possible to control the temperature of the reacting mass at every instant. The viscose obtained by mixing the xanthate is improved when the xanthate is obtained at the proper temperature. In the present invention an arrangement has been provided for the purpose, consisting of the double jacket 3 and the circulation of a heating or cooling fluid. Internal ribs 29 acting as baffles not only strengthen the apparatus, but also ensure a proper circulation of the fluid.

As above mentioned continuity through the double jacket is obtained even during the opening of the apparatus, by means of the flexible tubes 4 connecting both spherical caps and arranged at the opposite ends of one or more diameters; rapidly operable connections 30, mounted on valves 31 permit very easy removal of the flexible tubes, while by opening the above mentioned valves, very rapid complete discharge of the double jacket can be effected.

An advantageous construction which ensures the continuity of the circulation of the heating or cooling fluid in the double jacket consists in the provision of the admission and outlet conduits 32, 33 of the above mentioned jacket in the journal 7. This construction is further characterized by the feature that with only two flexible tubes 4, at opposite ends of a single diameter, the admission and outlet connections 34 and 35 of the double jacket are located in the plane of the flexible tubes. The circulation of the fluid agent owing to the distribution of the baffles, is from one half of the fixed cap to the mov-

able cap, and then back through the second half of the fixed cap.

In order to facilitate the loading of the apparatus, manholes 36 of suitable diameter are provided at a convenient height. The process is watched through the sights 37. The tightness of the joints of the manholes and of the sights is obtained by the use of suitable materials resistant to carbon bisulphide and having no roughness capable of retaining particles of material already treated or to be treated.

What I claim is:

1. Apparatus for the manufacture of cellulose xanthate comprising a pair of caps making joint, means for rotating said caps as a whole, and means for moving said caps apart axially.

2. Apparatus for the manufacture of cellulose xanthate comprising a pair of spherical calotte shaped caps making joint on the same small circle and having smooth internal surfaces, means for rotating said caps as a whole, and means for moving said caps apart axially.

3. Apparatus for the manufacture of cellulose xanthate comprising a pair of churn members making joint, means for rotating said churn members as a whole, means for moving said churn members apart axially, and means for guiding and limiting the relative motion of said churn members during such axial movement.

4. Apparatus for the manufacture of cellulose xanthate comprising a pair of churn members making joint, means for rotating said churn members and axial screw means on one of said churn members for moving it away from and towards the other churn member.

5. Apparatus for the manufacture of cellulose xanthate comprising a pair of double jacketed churn members making joint, means for rotating said churn members, means for moving said churn members apart axially, and flexible conduits coupling the jackets of said churn members.

6. Apparatus for the manufacture of cellulose xanthate comprising a pair of double jacketed churn members making joint, means for rotating said churn members, inlet and outlet conduits both joined to the jacket of one of said churn members, and baffles in said jackets to direct the flow therein of a temperature controlling medium from said inlet through half the jacket to which it is connected, thence through the other jacket, and thence through the other half of the jacket to which said outlet conduit is connected.

7. Apparatus for the manufacture of cellulose xanthate comprising a pair of churn members making joint, a journal on each said churn member, said journals being coaxial, means for rotating said churn members

through one of said journals, a screw formed on one of said journals, a nut meshing with said screw, means for rotating said nut with respect to said screw, and means for locking 5 said nut to said screw.

8. Apparatus for the manufacture of cellulose xanthate comprising a pair of caps making joint, means for rotating said caps as a whole, means for moving said caps apart 10 axially, nuts and bolts for holding said caps together and removable distance pieces on said bolts enabling said caps to move apart without removal of said nuts and bolts.

9. Apparatus for the manufacture of cellulose xanthate comprising a pair of double jacketed caps making joint, means including a journal on one of said caps for rotating said caps as a whole, means for moving said caps apart axially, two diametrically 20 opposite flexible tubes connecting the jackets of said caps, inlet and outlet conduits for a cooling medium formed within said journal, and pipes connecting said conduits with said jackets, said tubes, conduits and 25 pipes being arranged in a common axial plane.

10. Apparatus for the manufacture of cellulose xanthate comprising a pair of churn members making a circumferential joint, an 30 axial journal on each of said members, means for rotating one of said journals, and means for moving said churn members apart axially.

11. Apparatus for the manufacture of cellulose xanthate comprising a pair of hollow 35 members making a circumferential joint, means for rotating said hollow members as a whole, and means for moving said hollow members apart axially.

12. Apparatus for the manufacture of cellulose xanthate comprising a jacketed churn, an axial journal fast on said churn, means for rotating said journal churn, means for feeding carbon bisulphide axially of said 45 journal, and inlet and outlet conduits for circulating a temperature controlling medium in said jacket formed within and rotating with said journal.

13. Apparatus for the manufacture of cellulose xanthate comprising a pair of jacketed 50 churn members making joint, means for rotating said churn members, means for moving said churn members apart axially, and rapidly detachable flexible tubes connecting the jackets of said churn members.

55 14. Apparatus for the manufacture of cellulose xanthate comprising a pair of jacketed churn members making joint, means for rotating said churn members, means for moving said churn members apart axially, a valve on each of said jackets, and flexible tubes connecting said valve junctions.

In testimony whereof I have signed my name to this specification.

MICHEL DASSONVILLE.
